UNITED STATES PATENT OFFICE.

PATRICK J. McDONALD, OF NEW CUMBERLAND, PENNSYLVANIA.

LOADING MACHINE.

Application filed June 22, 1922. Serial No. 570,212.

To all whom it may concern:

Be it known that I, PATRICK J. McDONALD, a citizen of the United States, residing at New Cumberland, county of Cumberland, State of Pennsylvania, have invented a new and useful Loading Machine, of which the following is a specification.

My present invention comprehends a novel construction of a loading machine which is especially designed to be used to remove snow from public roads, compress it to a fraction of its original volume and load the compressed snow into any kind of a conveyor. It is adapted to be employed on streets, State roads, steam roads and trolley lines and can be mounted on tractors or on standard gage railroad trucks. It is also designed to be employed for grading streets and roads of any kind or for loading loose material such as iron ore, coal, sand or the like and is adapted to be employed in the soft ground of tunnels and subways for removing material.

It further comprehends a novel loading machine wherein I employ a novel construction and arrangement of a multiple bladed collecting scoop and novel construction and arrangement of conveyors adapted to receive the material discharged from said scoop and discharge it to other mechanism.

It further comprehends novel means for causing a circulation of a temperature changing mechanism to different parts of the mechanism.

It further comprehends a novel construction and arrangement of an auxiliary conveyor which is capable of rotary adjustment.

It further comprehends novel means for heating various parts with which the snow comes into contact during the operation of the machine.

Other novel features of construction and advantage will hereinafter more fully appear in the detailed description and the appended claims.

For the purpose of illustrating my invention, I have shown in the accompanying drawings a typical embodiment thereof which is at present preferred by me, since this embodiment will be found in practice to give satisfactory and reliable results. It is, however, to be understood that the various instrumentalities of which my inven-

tion consists can be variously arranged and organized and that my invention is not limited to the precise arrangement and organization of these instrumentalities as herein shown and described.

Figure 1 represents, in side elevation, a loading machine, embodying my invention.

Figure 2 represents a section on line 2—2 of Figure 1.

Figure 3 represents, in front elevation, a portion of the machine.

Figure 4 represents a section on line 4—4 of Figure 3.

Figure 5 represents, in sectional elevation, conveyor mechanism employed.

Figure 6 represents, in section, another conveyor mechanism employed.

Figure 7 represents a section on line 7—7 of Figure 3.

Figure 8 represents, diagrammatically, the driving mechanism.

Figure 9 represents, in side elevation, and partly in section, a snow removing element and plough in conjunction with a portion of the conveyor mechanism.

Figure 10 represents in section a fuel supply tank and certain of its adjuncts.

Figure 11 represents in sectional elevation, a loading element, in conjunction with which fuel supply tanks similar to that seen in Figure 10 are employed.

Figures 12 and 13 represent diagrammatic side elevations of the oil and water circulating systems.

Figure 14 represents a vertical sectional view through the rotary shovel, showing the hollow trunnions and water and oil connections.

Similar numerals of reference indicate corresponding parts in the figures.

Referring to the drawings.

1 designates a supporting framework which, as seen in Figure 1, is mounted on a tractor of the caterpillar type having the caterpillar treads 2 which may be coupled in any suitable manner, and are driven from the shaft 3 having the sprocket wheel 4 which drives the chain 5, which passes over the sprocket wheel 6 mounted on the shaft 7, which carries the larger sprocket wheel 8 which drives the chain 9, which passes around the sprocket wheel 10 mounted on the shaft 11.

The chain or endless apron 9 carries the caterpillar treads 2, and it will be apparent that the rotation of the shaft 3 by the motor 12, to be referred to, in the desired direction 5 will effect the propulsion of the tractor. The framework 1 supports a prime motor 12 of any desired construction, by which the main shaft 13 is rotated, see Figure 8, said shaft having the outer bevel gear 14 thereon. 10 The main shaft 13 has an inner bevel gear 15 thereon (see Figure 8) which is in mesh with the bevel gear 16, whereby the shaft 17 is rotated, said shaft being provided with a transmission 18 and a brake connection 19, 15 as seen in Figure 8, and being operatively connected with the drive shaft 3 by a sprocket chain or equivalent means 19^x of the tractor structure which I have designated as 20 in Figures 1 and 8. The bevel gear 14 seen in Figures 1 and 8 is in mesh with the bevel gear 21, which drives the shaft 22, 20 which is provided with a transmission 23 and a brake connection 24, said shaft carrying the bevel gear 25, which is in mesh with the bevel gear 26, which is mounted on the shaft 27, which carries the sprocket wheel 28. The sprocket wheel 28 drives the sprocket chain 29, which drives the sprocket wheel 30 mounted on the hollow shaft 31, 25 on which is supported the rotary shovel 32, whose construction will be apparent from Figures 3, 4 and 9. There may be two of the sprocket wheels 30 as seen in Figure 14, or only one as may be desired. The hollow shaft 31 which carries the sprocket wheel 30 and the rotary shovel 32 is mounted in oppositely located suitable boxes or bearings 33, one of which is shown in Figure 1, said bearings being capable of being raised or 30 lowered through the medium of the chains 34, which are located on opposite sides of the machine and pass around the drum 35, mounted on a shaft 35^x which is provided with the gear 36 in mesh with the worm 37. 35 38 designates the worm shaft upon which the worm 37 is mounted, said shaft rotating in suitable bearings 39 and 40 and having a handwheel 41 for rotating it, whereby it will be apparent that the rotation of the rod 38 and the worm 37 will rotate the gear 36 and the drum 35, thereby winding or unwinding the chain 34 thereon so as to raise or lower the boxes or housings 33 for the hollow shaft 31, whereby the position of the rotary shovel 50 32 can be adjusted vertically, according to the requirements of the work to be done. 55 The rotary shovel seen in Figures 3 and 4 is composed of the side plates 42, which are provided with the serrations 43 whose contour will be understood from Figures 4, 9, 12 and 13, and the space between the side plates 42 is occupied by the body 44 of the rotary shovel, which is composed of the inner star-shaped member 45 composed of 60 the transverse troughs terminating in the

apices 46 and the outer similarly shaped casting member 47, whereby a chamber 48 is formed between the members 45 and 47 in which the water pipes 49 are contained, the inlet to said water pipes being indicated at 50 and the outlet therefrom being indicated at 51 (see Figure 4).

The star-shaped body structure of the rotary shovel 44 may be composed of sheet metal plates which are suitably assembled 75 and joined together in any convenient manner, the outer converging terminals of the outer plates 47 being tied together and reinforced by the terminal transverse pointed members 52 which are provided with inner flanges 52^x secured to the members 47 in any suitable manner, the outer points 53 of said terminal members being coincident with the tooth portions 54 of the side plates 43, as will be understood from Figures 4 and 9. 80 The outer points 53 may be hardened by any suitable process to prevent wear, and a rotary shovel is thus produced having the outer serrated cutting edges 43, the transverse blades or points 53 and the intermediate transverse trough shaped portions, as seen in Figure 4.

It will thus be apparent that a very rigid, durable and powerful rotary shovel body is provided, which will be durable and efficient under all conditions.

It will be understood that as the rotary shovel 32 is rotated, the snow or other material which is excavated or taken up thereby will be thrown rearwardly upon the endless apron or conveyor 55 which passes around the lower roller 56 mounted on the shaft 57 and also around the upper roller 58 mounted on the shaft 59, which latter carries the gear 60, which is in mesh with and driven by the worm 61.

The worm 61 is mounted on the shaft 62, see Figure 1, which carries the lower bevel gear 63, which is driven by the main bevel gear 14, as will be understood from Figures 1 and 8, wherefrom it will be seen that the rotation of said bevel gear 14 drives in unison both the rotary shovel 32 and the conveyor belt 55, the latter travelling over and being supported by the intermediate rollers 64, which may be of any desired number or construction, and mounted or supported in any suitable bearings.

The main shaft 13 carries a pulley or sprocket wheel 65, see Figure 8, which drives the compressor belt 66, see Figures 5 and 8, said compressor belt driving the roll 67, which is mounted on the shaft 68. The roll 67 drives the compressor apron 69 which passes around the rollers 67 and 70, the general arrangement and position of the endless compressor apron 69 and the endless conveyor apron 55 being apparent from Figure 5 and from the dotted lines in Figure 1, in which figure I have omitted the

belt drive 66 for the sake of clearness of illustration.

I have termed the endless apron 69 as a compressor apron, as its function is to compress the snow or other material which is thrown upon the conveyor apron 55 by the rotary shovel 32, and I preferably collocate said compressor apron 69 with respect to the conveyor apron 65, as seen in Figure 5, so that said aprons converge upwardly so that the entrance opening between said apron as indicated at 71 is larger than the discharge space indicated at 72, whereby the snow or other material will be thrown upon the conveyor apron 55 will be compressed or compacted as it travels upwardly on the conveyor 55.

It will be understood that the shafts on the rollers 67 and 70 are mounted in suitable bearings or housings and that convenient adjustments which it is unnecessary to describe in detail may be provided for keeping the aprons 55 and 69 at all times sufficiently taut. The rotary shovel 32 is mounted in a suitable front framework or housing 73 whose general contour will be understood from Figure 3, being of inverted U-shape and composed of metal plates properly reinforced or bolted together. Above the frame 73 is pivotally secured the inverted U-shaped member or hood 74 which is pivotally secured at the points 74^x (see left hand of Figure 1) and is adjusted by the rod 73^x which is actuated by the handle 72^x, said hood serving to deflect the material towards the rotary shovel 32.

The front vertical plates 75 of the inverted U-shaped housing seen in Figure 3, are provided on each side with the vertical slots 76, through which pass the bolts 77, which also pass through the upwardly extending rear plates 78 which support the bottom shoe members 79 having the forward pointed ends 80 the object of this construction being best understood from Figure 7 and being to permit the raising or lowering of the side shoes 79 according to the character of the work to be done which can be quickly accomplished by loosening the bolts 77, as is evident.

In Figure 2, I have shown an enlarged sectional view of the bearings for the lower roll 56 of the conveyor apron 55, the shafts 57 of said lower roll 56 being mounted in the bearings 81 carried by the side frames 82, which are provided on each side with the inclined walls 83 and 84, arranged in pairs whereby a species of trough 85 is formed which receive the snow or other material excavated and thrown by the rotary shovel 32 upon the conveyor 55, there being a space 86 formed between said inclined walls 83 and 84 for the reception of the water pipes 87, whereby the sides of the trough 85 are heated.

It will be apparent that when the rotary shovel seen in Figure 4 is employed for removal of snow that it is desirable to keep the same heated to the requisite degree, which I effect by means of the water pipe 88 which leads from the water pump 89 seen in Figure 1 and in the diagrammatic view in Figure 13. The water pump 89 may be of any suitable construction, as a rotary pump, and is provided with a shaft 90 and a pulley 91 which is driven by a belt 92, which is actuated by a pulley 93, seen in Figure 8.

As the water pump is actuated in unison with the main shaft 13, it will be apparent that the water will be pumped through the pipe 88 into one of the pipes 87 of the trough walls seen in Figures 2 and 3 and thence through the pipe 94 seen in Figures 1 and 9 into the upper portion 94^x of the casing 121 and thence into the inlet pipe 50, see Figure 4, the water being withdrawn from the circulating system through the pipe 51 through which the water flows to the pipe 87 on the opposite side of the trough 85 seen in Figure 2, and thence through the pipe 106 to the lower water box 108 seen in Figure 5 and as shown diagrammatically in Figure 13.

In order to effectively heat the interior of the rotary shovel seen in Figure 4 and to keep the temperature in the water circulating system up to the desired point, I employ preferably a supply of oil and other suitable hydrocarbon which is contained in the oil tank 87^x and flows therefrom through the pipe 88^x to the oil pump 95, see Figures 8 and 12. The oil is forced by the oil pump 95 seen in Figures 8 and 12 into the oil pipe line 100, see Figures 5 and 12, said oil pump being provided with a shaft 96, carrying the pulley 97, which is driven by the belt 98, which is driven from the pulley 99 mounted on the main shaft 13. It will consequently be apparent that as the oil pump is actuated, oil will be forced therefrom into the oil pipe 100 seen in Figure 12 and thence into the burners 117 seen in Figure 5 by the pipe 118 and thence into the oil pipe 101 from which the oil flows from the branches 102 to the branches 103 and thence to the burners 104, access being had to said burners through ports 105.

It will consequently be seen that when the burners 104 are ignited they will furnish an adequate supply of heat for the interior of the rotary shovel and will heat the water which is contained in the water circulating system seen in Figure 4.

It will be understood from the foregoing that through the medium of the pipes 88, 87, 94 and 50 the forward portion of the apparatus is effectively supplied with water which is heated by the burners shown. In order to convey water to the conveyor appa-

ratus and its adjuncts seen in Figures 5 and 12, I employ the system of water piping comprising the lower water pipe 106, see Figures 5 and 13 and the upper water pipe 107 both of said pipes being connected with the water pump 89, see Figures 8 and 13. The lower pipe 106 leads into the U-shaped water box 108, see Figure 5, from which water is conducted by means of the pipe 109 to the next water box 110 from which the pipe 111 leads to the next water box 112 from which leads the pipe 113 to the next water box 114 from which leads the pipe 115 to the next water box 116, the water 15 flowing therefrom through pipe 107 already described back to the water pump 89. The water is supplied to the system through the funnel 115* and the pipe 116*, see Figure 5.

In order to heat the water contained in the water boxes 108, 110, 112, 114 and 116, I employ a series of burners which are indicated at 117 and are fed with oil or suitable hydrocarbon through the pipe 118 common to all the burners, the inlet to said pipe 118 being through the pipe 100, which leads from the oil pump 95, as already described, see Figure 12.

It will thus be seen from the foregoing that I make provision for supplying water to the spaces between the conveyor apron 55 and for supplying the requisite quantity of oil or hydrocarbon to the burners 117 so as to effectively heat all the water boxes seen in Figure 5, said water boxes and burners 35 being omitted from Figure 1 for clearness of illustration, but being clearly shown in Figure 5.

If desired the exhaust from the engine 12 can be conducted by the upper pipe 107* 40 and the lower pipe 106* to the upper and lower portions of the conveyor and utilized for heating purposes, said pipes discharging thereinto at the upper and lower points *a* and *b* (see Figure 5).

At the left-hand portion of Figure 1 and in Figure 9, I show an implement or plow 120, whose lower end is mounted in the housing 121 containing the water coil 122, the upper ends of said coil communicating with the pipes 50 and 94, said implement 120 being mounted upon the actuating rod 124 which passes through suitable guides as 125, see Figure 1, and is actuated by means of the handle 126, connected to the rod 126*, 55 there being an elbow lever interposed between the rods 124 and 126*. The upper portion of the plow casing at 94* is hollow and supplied with hot water as already explained.

It will be apparent from the foregoing that as the shaft 13 is rotated power is provided to propel the tractor 20 and in addition by means of the various connecting mechanisms, the shovel is rotated and as 60 the snow or other material is excavated by

the rotary shovel, it is thrown backwardly upon the conveyor apron 55 and as the material is conveyed upwardly by said apron it is compressed between the conveyor apron 69 and passes from the upper portion 70 of the conveyor apron over the guide or deflector 127 seen at the upper right-hand portion of Figures 1 and 5.

The snow or other material passing over the deflector, as indicated at 128, is deflected 75 into the hopper 133 by means of the rotary device 129 mounted on the shaft 130 which is driven by the belt 131 which is actuated by the sprocket wheel 132, so that the material 128 is properly deflected into the hopper 133, seen at the right of Figures 1 and 6.

The excavated material passes from the hopper 133 to the endless delivery apron 134, which passes around the lower roller 135 and the upper roller 136. The roller 135 is mounted on a shaft 137 which carries the sprocket wheel 138 which is rotated by the sprocket chain 139, which passes around the sprocket wheel 140, which is rotated by the shaft 141 driven by the engine or motor 90 142. The engine shaft 141 is provided with a pulley 143 which drives the belt 144 which drives the pulley 145 on the shaft 146 of the water pump 147. The water is forced from the pump 147 through the pipe 148 95 into the water box 149, see Figure 6, from which the water flows to the pipe 150 to the water box 151, which is connected to the water box 152 by the pipe 153. The water flowing from said box 152 through the pipe 154 into the coil 155 from which the water flows back to the water pump through pipe 156, said coil 155 being contained in the tapered deflector 157. The walls of the hopper 135 are provided with a chamber 158 100 in which the coil 155 is contained, the water being conveyed into said coil 159 from the water box 149 by the pipe 160 and leaving said coil 159 through the pipe 161 which is connected to the water box 151, see Figure 6. 110

Referring to Figures 6 and 8, the manner of heating the water boxes will be understood, the oil or hydrocarbon being forced from the oil pump 162, which is actuated by the pulley 163, belt 164 and pulley 165 115 mounted on the shaft 166.

It will be apparent that the rotation of the shaft 166 will force the oil or hydrocarbon in the oil tank 162* through the pipe 161* to the oil pump 162 into the pipe 167 120 and thence to the burners 168, 169 and 170, which are located in proximity to the water boxes 152, 151 and 149, respectively, see Figure 6.

The engine shaft 141 is provided with 125 a transmission 171, and the main shaft 13 is also provided with a transmission 172, see Figure 8, which transmissions are actuated by suitable controls, which need not be described in detail. 130

The discharge mechanism seen at the right of Figure 1, is mounted on the foundation 1 and provided with rollers 173, and may be rotated in any desired direction by suitable means, as the wheel 174, mounted on the shaft 175 which carries the pinion 176 in mesh with the stationary annular rack 177.

Power can be applied to the wheel 174 by the shaft 177 and gearing 178, as will be evident to those skilled in the art.

In Figures 10 and 11, I have shown another manner of heating the interior of the rotary shovel 32, which I have shown diagrammatically in Figure 11, said shovel having the spokes 179 mounted on the hubs 180, through which the shaft 181 passes to which the sprocket wheels 30 are secured. There are three compartments formed by the spokes, and in each compartment I locate the oil reservoirs 182, which are each supported by a pair of curved straps 183, which encircle the ball bearings 184, the construction being such that the oil reservoirs will always hang vertical and the oil will be fed by gravity to the burners 185. This construction dispenses with the piping seen in Figure 4. In Figure 14, I have shown in detail one arrangement of hollow trunnions for the oil and water connections seen in Figure 4, whose construction will be apparent without further description.

It will be understood that the compressor apron 69 and its adjuncts are heated by means of the branch pipes 186 and 187, which communicate with the water boxes 110 and 114 respectively, said pipes communicating with the hollow bearings of the rolls 70 and 67, which are connected by the outside pipe 188 shown in dotted lines in Figure 5.

The manually operated lever 189 seen in Figure 5 serves to operate the belt scraper 190, and the upper small rolls 191 and the lower small rolls 192 seen in Figure 5 serve to facilitate the crushing or the compacting of the snow or other material passing between the conveyer apron 55 and the compressor apron 69, these rolls 191 and 192 being mounted in suitable bearings of any character and are preferably positioned with respect to each other substantially as seen in Figure 5 within their respective aprons.

It will be understood that the heating appliances shown in connection with the rotary shovel and with the conveyor aprons are particularly useful when the device is used as a snow remover, and it will be apparent that when the device is used for grading streets or for loading loose material such as iron ore, coal, sand or the like, the water circulating and heating appliances may be dispensed with or thrown out of operation by the manipulation of suitable valves, which I have deemed it unnecessary to describe in detail.

It will be apparent that if desired the tractor construction seen in Figure 1 may be dispensed with and the apparatus can be mounted directly upon a standard gauge railway truck.

In Figure 4, I have shown the inner wall 45 of the rotary shovel as lined with asbestos at the point indicated, which serves to retain the heat within the shovel and I also show the pointed deflector seen at the right of Figure 6 as similarly lined with asbestos at the point indicated for a similar purpose.

Having thus described my invention, what I claim as new and desire to secure by Letters Patent, is:—

1. In a device of the character stated, a rotary shovel composed of serrated side plates and a body portion composed of transverse blades forming pointed teeth secured to said plates so as to provide pockets between said teeth, in combination with a conveyor apron located in the rear of said rotary shovel and adapted to receive the material thrown thereon from said shovel, and a compressor apron located above said conveyor apron and adapted to compress the material excavated by said shovel.

2. In a device of the character stated, a rotary shovel of star shape in cross section having pointed teeth and intervening pockets, an inclined conveyor in the rear of said shovel, a compressor apron above said conveyor for compacting the material on said conveyor, a prime motor and power transmission devices leading therefrom for actuating said shovel, conveyor and compressor apron in unison.

3. In a device of the character stated, a rotary shovel of star shape in cross section having pointed teeth and intervening pockets, an inclined conveyor in the rear of said shovel, a compressor apron above said conveyor for compacting the material on said conveyor, a prime motor, and power transmission devices leading therefrom for actuating said shovel, conveyor and compressor apron in unison, in combination with a hopper located under the upper end of said conveyor to receive the discharge therefrom, and an apron below said hopper for conveying the material discharged thereinto to the desired point.

4. In a device of the character stated, a rotary shovel, a housing therefor, adjustable shoes on the sides of said housing, means for raising and lowering said shoes, and means for locking said shoes in the desired adjusted position.

5. In a device of the character stated, a rotary shovel, composed of serrated side plates, a body portion composed of transverse pockets, and blades terminating in transverse teeth, which extend between said side plates, vertically movable boxes for supporting the journals of said shovel, and

- means for raising and lowering said boxes and shovel.
6. In a device of the character stated, a rotary shovel, composed of side plates, a body portion composed of transverse pockets and transverse blades terminating in transverse teeth, which extend between said side plates, said body being composed of inner and outer members having a space therebetween, hollow trunnions for said shovel, and water circulating pipes located in said space and having their inlet and outlet passing through said trunnions for heating said shovel.
- 15 7. In a device of the character stated, a rotary shovel composed of side plates, a body portion composed of transverse pockets and transverse blades terminating in transverse teeth, which extend between said side plates, said body being composed of inner and outer members having a space therebetween, hollow trunnions for said shovel, and water circulating pipes located in said space and having their inlet and outlet passing through said trunnions for heating said shovel, in combination with burners located within said shovel for heating the latter and said pipes, and means for supplying hydrocarbon to said burners.
- 20 8. In a device of the character stated, a rotary shovel, an inclined conveyor in the rear of said shovel for receiving the material therefrom, means for actuating said shovel and conveyor in unison, and means for heating said shovel and conveyor.
- 25 9. A hollow rotary shovel, hollow trunnions therefor, means for rotating said shovel, water connections leading through said hollow trunnions to the interior of the shovel, oil pipe connections also leading through said hollow trunnions, and burners supported within the interior of said shovel and in communication with said oil pipe connections for heating the interior of said shovel.
- 30 10. In a device of the character stated, a frame-work, a rotary shovel mounted in the front portion thereof and provided with transverse pockets and blades forming teeth, serrated side plates to which said blades and pockets are secured, a housing for said shovel having its lower front portion provided with shoes, means for vertically adjusting said shoes, and a scoop attached to the front of said frame-work and overhanging said rotary shovel.
- 35 11. In a device of the character stated, a frame-work, a rotary shovel mounted in the front portion thereof and provided with transverse pockets and blades forming teeth, serrated side plates to which said blades and pockets are secured, a housing for said shovel having its lower front portions provided with shoes, means for vertically adjusting said shoes, a scoop pivotally attached to the front of said frame-work and overhanging said rotary shovel.
- 40 12. In a device of the character stated, a prime motor, a rotary shovel, power transmission devices intermediate said motor and shovel for rotating the latter, a tank for hydrocarbon, a pump into which the hydrocarbon is conducted from said tank, said pump being operated by said prime motor, an inclined conveyor, water holding devices in said shovel and conveyor, burners located in proximity to said water holding devices in said shovel and conveyor, and a pipe leading from said oil pump to said burners.
- 45 13. A hollow rotary shovel, hollow trunnions therefor, means for rotating said shovel, water connections leading through said hollow trunnions to the interior of the shovel, oil pipe connections also leading through said hollow trunnions, burners supported within the interior of said shovel and in communication with said oil connections for heating the interior of said shovel, a prime motor, a water pump for forcing water through said water connections, and an oil pump communicating with said burners for forcing oil under pressure thereto.
- 50 14. In a device of the character stated, a housing, a rotary shovel mounted in the front portion thereof, an inclined conveyor at the rear of said rotary shovel, an upwardly movable implement located between the lower end of said conveyor, and the rear of said shovel, means for actuating said implement, a hopper located below the upper end of said conveyor, an inclined apron below said hopper for receiving the material discharged thereinto, and means for rotating said hopper and the apron below it in any direction to discharge the material excavated.
- 55 15. In a device of the character stated, a housing, a rotary shovel mounted in the front portion thereof, an inclined conveyor at the rear of said rotary shovel, an upwardly movable implement located between the lower end of said conveyor and the rear of said shovel, means for actuating said implement, a hopper located below the upper end of said conveyor, an inclined apron below said hopper for receiving the material discharged thereinto, means for rotating said hopper and the apron below it in any direction to discharge the material excavated, means for heating the interior of said shovel, means for heating both of said conveyors, and means for heating the side walls of said hopper.
- 60 16. In a device of the character stated, a housing, a rotary shovel mounted in the front portion thereof, an inclined conveyor at the rear of said rotary shovel, an upwardly movable implement located between the lower end of said conveyor and the rear

- of said shovel, means for actuating said implement, a compressor apron located above said conveyor, a hopper located below the upper end of said conveyor, an inclined 5 apron below said hopper for receiving the material discharged thereinto, means for rotating said hopper and the apron below it in any direction to discharge the material excavated, inclined walls located on opposite 10 sides of the lower portion of said conveyor in the rear of said shovel, and means for heating the space between said inclined walls.
17. The combination of a tractor, a frame-work mounted thereon and carried thereby, a rotary shovel mounted in the forward portion of said frame-work, an inclined conveyor in the rear of said shovel, a turn table located on the rear portion of said tractor, 20 a hopper located below the upper end of said inclined conveyor for receiving the material excavated, and an inclined apron below said hopper for conveying the material discharged thereinto to the desired 25 point.
18. The combination of a tractor, a turn table mounted thereon, an endless apron supported by said turn table, means for actuating said apron, a hopper located above said 30 apron, a motor carried upon said turn table, an oil tank also carried on said turn table, water circulating pipes leading through said hopper and through said conveyor, means for forcing water through said conveyor 35 and the walls of said hopper, and means for supplying oil under pressure to burners located in proximity to said water pipes.
19. In a device of the character stated, the combination of a rotary shovel, a conveyor apron in the rear thereof, and a plough located intermediately of said rotary shovel and apron, said plough being adapted to be reciprocated in a suitable casing, and means for heating said casing.
20. In a device of the character stated, an inclined conveyor apron, upper and lower intermediate rolls therefor, a plurality of water boxes positioned between said rolls, means for supplying water to said water boxes, the latter being in communication with each other, burners for each of said oil boxes, and means for supplying a hydro-carbon to each of said burners.
21. In a device of the character stated, an endless delivery apron, upper, lower and intermediate rolls therefor, a hopper located above said delivery apron and discharging thereupon, water boxes positioned between the rolls of said delivery apron, connections from said water boxes to heating coils for heating said hopper, means for circulating water through said water boxes, burners for heating said water boxes, and means for forcing oil into said burners.
22. A rotary shovel composed of inner and outer walls forming transverse troughs and blades, the outer ends of said blades being reinforced by transverse pointed members, a lining of asbestos for the space between said walls, water holding devices in said space, and means for heating said water holding devices.

PATRICK J. McDONALD.
